GRADING MACHINE

Nathan Bretholtz, Worcester, Mass., assignor to
 Bretholtz Manufacturing Company, Worcester,
 Mass., a corporation of Massachusetts

Application March 9, 1934, Serial No. 714,834

52 Claims. (Cl. 33—148)

This invention relates to leather grading machines and more especially to an improvement on the Nichols type of grading machine illustrated in the Nichols Reissue Patent 12,288 and 5 in the later Nichols Patent 1,130,321. More particularly, my invention relates to an improvement in the edge grading of soles, or other die cut parts such as contemplated by Nichols in Patent No. 841,809 issued January 22, 1907, and in his 10 later Patent 1,009,988.

In the grading of leather soles, which will be referred to preferably as exemplifying or representing a typical die cut piece which is to be graded, it is desirable to obtain a final indication 15 of the thickness of the thinnest edge portion of the sole. The grading of the soles in this manner is important because it is the edge of the sole which is determining in the specification of commercial thickness of the sole, and it is the 20 edge of the sole which is gauged by hand to verify machine grading.

In the prior art as represented by the Nichols reissue and by the later Nichols Patent 1,130,321, it was customary to pass a sole between a pair 25 of feeler rolls, one of the rolls being movable in accordance with the varying thickness or thinness of the sole, whereby to set or control a pawl and ratchet mechanism so as to measure the thinness of the sole, a further mechanism being 30 utilized to lock the measuring indicator in its final minimum thickness indicating position, just before the sole passed out of the machine. The machine as developed by Nichols and his assignees, I have found to be insufficiently sensitive. 35 For instance, the Nichols rolls, because of their relatively great length, I have found to be unable to follow pockets in a sole, and unable to detect relatively thin edge portions, so that the final measurement obtained is, to a considerable extent, unreliable.

Because of this unreliability, it is necessary 45 for the sole grader to set the machines to grade soles at grades lower than actual, or to use check up men who arrange groups of the soles on end, once they have been graded and evened, and pick 50 out of the groups those soles which have relatively thin spots which have been missed by the grading machines. Naturally, this creates considerable expense, and where soles are shipped to customers by manufacturers and are found 55 to be of less thickness than specified by order, there is considerable loss of good will.

Before the development of the Nichols machine just described, there was developed in the art, an

edge grader shown in Patent 841,809 where relatively narrow grading rolls were used, those rolls being mounted for vertical movement, and also for lateral movement, and guided by feeler devices in contact with the soles. Therefore, in 5 Nichols, the grading rolls were adapted to follow more or less the contour of the soles. However, as will be readily appreciated, a sole or any other die cut body naturally has curves, and the radius of curvature of the curves being relatively great 10 in relation to the line of travel of the soles, the measuring rolls in moving laterally developed considerable friction against the leather surface of the soles so that there was a binding action, and a great many errors crept in. For instance, 15 it will be readily appreciated that with a sole moving longitudinally through the Nichols machine of Patent 841,809, when a point of relatively great increase of curvature or decrease of curvature is reached, there will be a relatively rapid 20 movement of the detecting rolls directly at right angles to the direction of travel of the sole. There would, therefore, be a tremendous amount 25 of friction set up which would probably affect the reading. In reality, the rolls did not follow the sole contour because they could move only at right angles to the travel of the sole and not in line with the particular curvature of the part 30 of the sole then in contact with the rolls. This defect is inherent in any machine in which the measuring rolls must move bodily with the mechanism on which they are mounted.

It will readily be appreciated also, that in the Nichols machine, unless the grading rolls were extremely wide so as to be insufficiently sensitive 35 to measure the edges of the soles, they would run off the soles at sharp changes in curvature.

In view of all these difficulties the Nichols patented device was never a commercial success and was abandoned in favor of the edge grader 40 illustrated in Patent 1,009,988 where a balanced plate was used, the plate being hollowed out so as to be affected only by the edges of the soles and to operate the indicating mechanism by a tipping movement which in itself was extremely 45 undesirable. This type of edge grader was never commercially successful, and along with the roll edge grader, was abandoned for the present long roll type first described, and which is not capable of edge grading. A patent to Denne, No. 50 1,651,588, also attacks the problem of edge grading. In Denne, the measuring rolls are mounted for vertical movement on swinging arms. While, therefore, Denne will have a somewhat better action than the action of the earlier devices in 55

this art, yet he does not obtain true edge grading because his roll moves bodily with the measuring arms and will not give the results obtained from my contribution to this art, as will be explained 5 presently.

In order to devise an edge contour grading machine, and yet avoid the difficulties inherent in the prior art constructions discussed above, I mount my measuring rolls for rotation on a pair 10 of follower measuring arms which are pivotally mounted on the machine frame and have guide means in contact with the edges of the sole for guiding the arms on their pivots as the curvature of the sole in contact with the guiding means 15 changes. The measuring rolls are mounted for vertical movement relatively to the measuring arms and are adapted to actuate the measuring devices.

The measuring rolls, in order to follow perfectly the contour of the soles, I have found 20 should not be mounted in fixed relation to the pivoting arms. I have found also that the rolls should not be mounted for swivelling on a vertical bearing in dead center relation to their point 25 of contact with the soles, since then it would not be possible for the rolls to follow the contours perfectly, and there would be at least some of the defects of the prior art present. I mount my measuring rolls as casters whose axis of rotation 30 is offset relatively to their point of contact with the soles. The measuring rolls therefore have a caster effect relatively to the soles so that as the rolls move bodily with their pivot shafts and measuring arms, as induced by the contact of the 35 measuring arm guides with the soles, the rolls will also swivel on their pivot shafts to conform to the actual contour of the soles. In this way, the rolls may be made just as narrow and as sensitive as desired, and may be mounted to follow 40 the sole edge in any relation thereto that may be desired, and regardless of the feeding speed.

Preferably I mount my rolls so that their centers lie directly on the edge of a sole traversing 45 the machine so that when the sole inclines down from its edge it will nevertheless be the sole edge which will lie under the roll center, and which will control. I have also a further feature incorporated in my machine whereby the measuring 50 rolls will be rendered even more sensitive in measuring the edge thickness of the soles. I mount the measuring rolls so that should the sole incline upwards from its edge, the roll will align itself with that inclined surface so that its 55 center measuring portion will be in contacting position with the sole, rather than only its inside edge. Preferably, the detailed construction whereby the measuring roll is so mounted, embodies a self aligning ball bearing which not only 60 allows for free rotation of each roll, but allows each roll to tilt on its bearing as will be quite clear to those skilled in the art.

In order to insure the proper initial positioning of the measuring rolls relatively to the soles, I 65 provide means which are engaged by the soles upon entering the machine for lifting the measuring rolls a predetermined distance which I prefer shall be substantially equal to the thickness of the soles contacting the actuating means. 70 I then provide further means contacted by the soles as they enter further into the machine for releasing the measuring rolls for movement into contact with the soles. This is a very important arrangement and differs substantially from the 75 prior art in which the soles actually force the

measuring rolls apart by direct contact, or where the measuring rolls are moved by the mechanism feeding the soles into the machine automatically.

It is a further object of my invention to so mount the measuring arms and the measuring rolls that the rolls will not be urged by tremendous pressure into a sole contacting position, but will, rather, be lightly urged against the soles so as not to compress the same, and yet, with no loss of accuracy. 10

In the type of grading machine with which my invention is concerned, it is customary to have an indicating mechanism which is spring pressed in a direction to follow the movements of the measuring rolls as they move to indicate increasing thickness, the indicator being positively moved, however, by the measuring rolls in a direction to indicate decreasing thickness, or, to better state the operation, increasing thinness. Also, it is customary to provide pawl and ratchet 20 mechanism so that during the measuring of the soles, once a particular indication of thickness is obtained, only variations in a direction indicating greater thinness or decreased thickness is allowed. Thus, as the rolls move in a direction 25 to indicate greater thinness, the indicator will be moved positively, but should the rolls move in a direction to indicate increasing thickness, the pawl and ratchet mechanism will prevent a like movement of the ratchet. Since the spring 30 mechanism tending to move the indicator in a direction to indicate increasing thickness has a certain amount of inertia which must be overcome by the rolls in moving the indicator in a reverse direction, and since no thickness indication greater than the first indication is of any 35 value, I provide means for relieving the indicator from this spring tension once an indication of thickness is transferred to the indicator, so that thereafter there will be no spring tension urging the indicator into a thickness indicating direction, and so that the thinness movement of the indicator will then not be resisted in any substantial manner. This is an important feature in the smooth and accurate operation of my mechanism. Incidentally, I prefer to operate this 40 spring tension device simultaneously with the operation of the thinness measuring pawl I shall discuss later. 45

My invention also relates to certain means provided to control the initial actuation of the caster measuring rolls. It will be readily appreciated that as a sole enters the machine, and comes in contact with the caster rolls, it will tend to strike those caster rolls and swing them to one 55 side in a rather abrupt fashion, and if the sole is slightly bent on one of its edges, it may even contact the sides of the caster rolls, sweep them aside, and thus render them inoperative. Therefore, I provide a locking arm which is adapted to 60 drop in back of the caster measuring rolls just as the sole enters the machine, whereby to lock the caster rolls against movement relatively to the measuring arms until the sole has advanced just beyond the rolls, but at the same time allowing the arms with all their parts to move out and follow the sole contour. Preferably, I provide these locking means and arrange them to be operated simultaneously with the operation 65 whereby the measuring rolls are lifted to an extent substantially the thickness of the sole. I also release the rolls simultaneously with the release of the rolls into a downward measuring position, so that they may swivel freely thereafter to follow the sole contour. 70

It is a further object of my invention to provide a modification for measuring square heeled soles. I utilize in this modification, the measuring roll locking means to swing to one side the measuring arms so as to permit the sole to enter between the arms.

As I have already indicated, I use the pressure of the sole itself against the rolls to force the arms carrying the measuring rolls into an upward position, transmitting to the measuring rolls a movement substantially equal to the thickness of the sole. I also provide additional means for releasing the rolls for movement downward into measuring position, which are also actuated by the sole as it further passes through the machine. In addition, I also operate the other controls for the machine by the sole per se. Thus, I provide a further roll which is moved by the sole in passing through the machine for moving the holding pawl of the thinness measuring ratchet into cooperation with that ratchet. I also provide a gate which is actuated by one sole into a position to prevent the entering of a second sole into the machine. In the preferred embodiment of my invention, the means for moving the pawl into the thinness measuring ratchet, are integral with the means for moving the gate into a lower position for locking out further soles. I then provide additional mechanism which is operated to drop, upon the passing of the sole through the machine, this additional mechanism being adapted to lock the holding pawl into the final indicating ratchet. In this way, I overcome the necessity of providing gears or timing mechanisms since the sole is a perfect timer in itself of the operating mechanism in the machine.

Also, the sole operated mechanism operates practically all the controls in both their forward and reverse movements. Thus the roll that actuates the gate also releases it, and the thinness pawl is similarly operated in and out of holding position by the upward and downward movement of a sole controlled roll. It is this in and out control of the various means, by the insertion of the sole between the various control rolls, and by the outward movement of the sole relatively to the control rolls, that is exceedingly important in the operation of the machine.

The guide or sole positioning device which centers the sole relatively to the machine so that it may be properly admitted into the same, forms an important part of my invention. Preferably, this centering device embodies a relatively fixed member or guide against which the initial end of the sole entering the machine, that is the heel portion, is forced by spring pressed arms. This relatively fixed guide will naturally insure the proper positioning of the sole as it enters the initial rolls of the machine. However, when the wide portion of the sole or the portion corresponding to the ball of the foot, comes opposite the relatively fixed guide, it will be understood that the sole will have been thoroughly grasped and held by the rolls of the machine, and I therefore provide means whereby the relatively fixed guide may be moved to one side to permit the sole to enter freely into the machine. Thus, the relatively fixed member is really held in a so-called fixed position by a very powerful spring which is capable of overcoming the pressure exerted against the sole by the positioning arms, the relatively fixed guide member being adapted to give way as the wide portion of the sole comes opposite it in its entrance into the

machine, the sole having then been securely grasped by the machine rolls.

In machines of the class indicated, it is customary for a sole to be passed through the machine, and for the operator to read the indication, after which he takes the particular sole and throws it into a bin corresponding to the indication. It is therefore necessary for the operator to first read the indicator, then focus his eyes on the bin to determine into which compartment the sole should be thrown, and then move his eyes back to the machine. Because of this necessity for the movement of the eyes back and forth at high speed, and because the average operator is required to do about 12,000 soles a day, a considerable amount of error creeps into the sorting operation. It is an object of my device to arrange for a signalling system operated by the machine whereby this movement of the eyes of the operator will not be necessary, and whereby the operator will have only to keep his eyes on the bin of the machine and never on the indicator.

I therefore provide with my invention a bin having a series of sole holding compartments adapted for different sizes of soles. In front of each compartment I place an electric filament bulb which is so interconnected with an electrical circuit through the machine that when the final measurements of a sole is reached, the filament will be rendered incandescent in the bin compartment corresponding to the particular measurement. I also arrange for a condenser in the circuits of the lighting filaments so that after the circuit through a particular bulb has been made and then re-opened for the measuring of a second sole, the condenser will function so that the light will remain on for an interval sufficient to focus the operator's attention thereon. Preferably, in detail, I utilize a series of contact points opposite the ratchet teeth of the indicator locking ratchet. The pawl of the indicator locking ratchet carries a spring contact adapted to make contact with the ratchet contacts and to close a circuit through one of the contacts and then through a particular bin compartment filament when the locking pawl is urged into locking relation with the indicator locking ratchet. Incidentally, where I employ my electrical system I arrange to release the final as well as the thinness measuring pawl from locking position as a measured sole leaves the machine. Otherwise I release each one independently by the soles.

While I have thus explained several objects of my invention, it will be understood that a further detailed description of the invention will indicate considerably more points of importance and to which my patent monopoly should extend. Also, it should be understood that practically any of the features which I have disclosed in particular may probably be readily modified or changed in many ways, perhaps to give even better results, or to give results equally as good as those inherent in my machine. Therefore, while I have shown a particular efficient embodiment of my invention, it should be understood that I consider my invention to be of relatively broad scope in this particular art, especially insofar as it pertains to the mounting and operation of the measuring rolls, the control of the various devices in the machine by the sole in an in and out direction, the arrangement of the measuring ratchets, and the provision of the signaling system, and I feel myself entitled to a

relatively broad monopoly under the patent law. Referring now more particularly to the drawings, Fig. 1 shows an elevation of my machine and illustrates the power means for driving the feed rolls of the devices. Fig. 2 is an enlarged elevation and partial section of the machine taken centrally through the machine. Fig. 3 is a sectional view through one of the measuring rolls and its mounting means. Fig. 4 is a top view of the machine taken substantially along the lines 4—4 of Fig. 2 and illustrates particularly the guide mechanism and the operation of the measuring arms on their pivots. Fig. 5 is a detail view showing more specifically the 15 operation of the guiding means for guiding the soles into the feed rolls. Fig. 6 is a partial view similar to Fig. 2 showing the parts in less detail and illustrating the operation of the means for elevating the measuring arms just prior to the 20 movement of a blank under the measuring rolls. Fig. 7 is a view showing some of the parts of Fig. 2 whereby the moving blanks control the entrance gate, the indicating lever tensioning means and the thinness measuring pawl. Fig. 25 8 is a front elevation of a measuring roll and the measuring arm guiding means. Fig. 9 is a view taken along lines 9—9 of Fig. 8. Figs. 10, 11 and 12 illustrate the positions that may be assumed by the measuring rolls relatively to a moving 30 blank and depending upon the configuration of the edge of the moving blank.

Fig. 13 illustrates the position of the measuring rolls relatively to a moving blank and shows just how the measuring rolls adapt themselves 35 to the curvature of the moving blank. Fig. 14 illustrates the cooperation of the final locking pawl with its ratchet, in the modification where-in the final locking pawl is adapted to close the circuit through an indicator in the bin with 40 which the grading machine cooperates. Fig. 15 illustrates the electrical circuit involved, while Fig. 16, illustrates a bin which, is used in my invention. Fig. 17 is a top view of the controlling ratchets for the indicating lever and shows 45 the operation of the pawl mechanism cooperating with the ratchets. Figs. 18 and 19 are views of the final locking pawl and ratchet in their two possible positions. Figs. 20 and 21 illustrate the operation of the means for controlling 50 the final locking pawl and ratchet and show the control means in the positions they will occupy when the locking pawl is in positions 18 and 19. Fig. 22 illustrates a square heeled sole, while Fig. 23 illustrates the modification whereby the 55 arms are swung aside to accommodate a square heeled sole.

Referring now more particularly to the drawings, reference numeral 10 indicates a main side plate of the machine, there being a side plate 60 at each side of the machine. An electric motor 11 operates through a belt 12, a pulley 13, which in turn operates through a chain belt 14, a gear 15 having thereon a smaller gear 16 which through chain belts 17 and 18 drives gears 19, 20' and 21' secured to the driving rolls 19, 20 and 21.

Referring now more particularly to Figs. 2, 3, 4, 8 and 9, reference numeral 22 indicates a measuring arm. There are two of such measuring arms in my machine, each of which is a duplicate of the other except that it is reversed in its operation relatively to a moving blank. For the sake of clearness I shall refer to one arm and its attendant mechanism, throughout the 70 description, it being understood, of course, that

there are two arms, each operating in the same manner. The arm 22 is mounted by means of a pivot shaft 23 on an integral block 24 extending from the frame of the machine, and is adapted to pivot on the shaft 23, being spring pressed, however, by a spring 25 toward a central position in the machine as determined by a stop member 26 integral with the arm and cooperating with an adjustable stop screw member 27 (Fig. 4). 5

There is secured to the arm 22, as by bolts 28 10 illustrated in Fig. 2, a downwardly extending arm 29 which terminates in a guide foot portion 30 as is best shown in Figs. 6 and 8. This guide foot 30 is adapted to impinge against a blank moving through the machine so as to cause the 15 arm 33, against the pressure of spring 25, to follow the contour of the particular blank moving through the machine.

There is pivoted on the arm 22, at point 32, a lever 31, which lever is further pivoted by means 20 of pivot shaft 33 as best shown in Figs. 2, 3 and 6, to a vertical arm 34, this arm having ball bearings at 35 and 36 whereby its pivotal relation to the shaft 33 and lever 32 is free from frictional resistance and allows for free pivotal movement 25 about the axis 33. This vertical member 34 carries at its lower end, and by means of the ball bearing 37, and shaft 37a, the rotating bearing portion 38 of a caster measuring roll 39, which in turn is mounted on self aligning ball 30 bearing 40 about the shaft 41 carried by the rotating member 38. As shown better in Fig. 8, the rotating caster member 38 carries a pin 42 adapted to impinge against a limit member 43 carried integrally with the vertical member 34 35 so as to limit the rotation of the caster member 38 as induced by a spring 44 mounted between the caster member 38 and the vertical guide foot or flange member 30.

It is readily seen, by glancing at Figs. 2 and 6 40 especially, that the vertical bearing 37 about which the caster member 38 is free to rotate, is offset relatively to the point of contact of the measuring wheel 39 with a blank moving through the machine, so that there will be a caster effect 45 created as between the measuring wheel 39 and the blank, this being utilized as will be indicated more particularly hereinafter.

The vertical member 34, in addition to being pivotally supported relatively to the shaft 33 by 50 its ball bearings 35 and 36, is also connected pivotally as through the shaft 45 and ball bearing 46, with the measuring lever 47, which in turn is connected pivotally as through a ball bearing 48, with the measuring arm 22. It will 55 be readily observed that any vertical movement of the member 34, because of its pivotal relation to the lever 31 and the measuring lever 47, will be with the member 34 maintained substantially 60 perpendicular to the sole as determined by the particular parallelogram arrangement. Actually, the member 34 is maintained always in a fixed 65 angular position so as to maintain the swivelling axis of the measuring roll perpendicular to the plane of the sole. It will be understood that 70 vertical movement will be transmitted to the member 34 by the measuring roll 39 as movement is transmitted to the measuring roll 39 by a blank moving through the machine. The vertical distance traversed by member 34 will be 75 equal exactly to the thickness of the sole, regardless of the rotated position of the roll 39 contacting the sole. Since member 34 is connected to lever 47, it will move the end of the lever 47 through a path directly proportional to 75

the thickness of the sole. Naturally, the other end of the lever 41 will also move proportionally to the thickness of the sole to actuate the indicating mechanism.

5 In order to stabilize the arm 34 and maintain it in a downward position and therefore maintain the roll 39 against a moving blank, I prefer to utilize a rod 50 secured at 51 to the arm 31 and adapted to be pressed by the spring 52 so as to transmit a counterclockwise rotation to the lever 34 about its pivot 32 on the arm 22, and thus tend to force the measuring roll 39 against a moving blank. The spring tension of the spring 52 is relatively light, and will be such as to permit 10 the roll to press but very lightly against the sole, it being entirely unnecessary for the roll 39 to act as a compressing agent for the sole, the sole being maintained in a depressed and flat position by feed and controlling rolls which will be 15 described hereinafter, and by a pressure stationary plate 52a cooperating with a fixed plate 52d and between which the sole is moved. A bottom plate 52b is used as a base measuring plate and is carried by roll 52c (Fig. 2). At this point it 20 should be indicated that the bottom plate 52b is of such width that regardless of the rotation of the measuring wheel 39 within the usual limits of sole curvature, the wheel 39 will have as a measuring support therefore this plate 52b.

25 30 It will be best at this point to describe briefly the operation and the advantages of the construction of measuring roll 39 and the moving vertical member 34 whereby thickness indications are transmitted to the measuring lever 41.

35 As a blank moves through the machine, it will contact the guiding flange 38 for moving the arm 22 against the pressure of the spring 25 in conformance with the particular contour of the moving blank. If the contact point of the measuring roll 39 were in line with the bearing 37 of its mounting member 38 on the vertical member 34, it will be readily understood that the measuring roll 39 would simply move with the arm 22 as an integral portion, in so far as side 40 or lateral movement were concerned. Naturally, as the contour of the sole or blank changed, as is illustrated in Fig. 13, there would be created a distinct frictional rubbing relation between the measuring roll 39 and the blank 55 which would 45 have to be overcome as the measuring roll moved laterally relatively to the blank. Also, at such points where there might be a relatively great increase of curvature, and with the measuring roll mounted with its central point directly over the edge of the moving blank, there would be 50 considerable danger of at least a portion of the measuring roll being pushed off the blank so that the edge of the blank cooperating with roll 39 would then act to control the movement of the arm 22 relatively to the blank, rather than the guide foot 30, as is intended. Therefore, with 55 the roll 39 in axial alignment with its bearing on the vertical member 34, the operation, while perhaps superior to that of the prior art, would be liable to considerable error in many ways, and would, in general, be considerably less desirable than the preferred embodiment of my invention.

60 I have also considered using guide members for rotating a measuring roll on its axis, where the axis is central relatively to the measuring roll, the guide members to be actuated by the sole, but this method of operation I have also found to be decidedly inferior to the simple 65 caster action I have disclosed herein.

I have, as has already been generally indicated, mounted the measuring rolls 39 in offset or caster relation to their bearings on the member 34, so that the rolls 39 will have a caster effect relatively to the moving blank, this caster effect or arrangement being effective to guide the rolls 39 in practically perfect alignment with the edge contour and with their exact center in practically perfect contact with the edge of the moving blank. In this way I avoid the disadvantages 10 indicated *supra*. The rolls are guided by the sole to follow the sole contour, this guiding being effected through the friction between the rolls 39 and the sole and through the guiding movement of the arms 22 through the flanges 30. The 15 offsetting of the axis of the rolls 39 allows them to swivel relatively to the arms so as to properly adjust themselves in the manner of casters relatively to the contour of the sole, as will be readily understood by those skilled in the art. This 20 relation of the measuring rolls relatively to the moving blank, in this case, a sole, is illustrated in Fig. 13 showing the measuring rolls in contact with the blank in several places of different curvature.

25 My invention involves a further interesting construction in so far as it relates to the mounting of the measuring rolls 39. Fig. 10 illustrates the position which would be assumed by a measuring roll relatively to an edge, if the measuring 30 roll were mounted on a usual rigid bearing. As is shown here, the sole 55 tapers downwardly towards its edges, and the roll 39, because it is in a rigid bearing relation to its shaft 41, is unable to assume an angle complementary to the 35 angle of the blank. Its center therefore does not measure the edge thickness, but the thickness just off the edge. This is error. I avoid this rejection by mounting my roll 39 on a self aligning bearing so that it may tilt freely relatively 40 to its shaft 41 and follow the contour of the edge of the sole as best illustrated in Fig. 11 where the sole is shown as inclining upwardly from its edge, and as shown in Fig. 12, where the sole declines downwardly from its edge.

45 In a machine of the type with which my invention is concerned, it is usual to permit the sole itself to contact the measuring rolls and to elevate those rolls initially and then to maintain them in a thickness indicating position until the 50 sole passes out from under the rolls. In some automatic self feeding machines, means have been provided to raise the rolls, these means being operated by the sole feeding mechanism. It was indicated *supra*, that as one of the features 55 of my invention I provide means whereby the proper initial positioning of the measuring rolls relatively to the soles is facilitated.

For this purpose, I provide means which I will now describe with special reference to Figs. 2, 4 60 and 6. On a pivot shaft 56 on each of the side and main plates 10 there is mounted a lever member 57 which extends substantially horizontal for a relatively short distance and then extends vertically for a short distance and then 65 downwardly again terminating at a point 58, and supporting a pivot shaft 59 adjacent said terminating point 58. On this pivot shaft 59 there is secured an upright control lever 60 which is adapted normally to underlie the extension arms 61 of a sleeve member 62 mounted for rotation about the shaft 63 supported by the side plates 10. The sleeve member 62 in turn carries a control rod 64 which is adapted to extend horizontally 70 so as to overlie at its ends the measuring levers 75

47, which it will be recalled are operated by the vertical movement of the measuring rolls 39 through the intermediary of the vertical members 34. The positioning of the sleeve 62 and the rod member 64 relatively to a measuring lever 47 is normally such, that when the spring 52 through its rod 50 has urged the measuring rolls downward into a position indicating zero thickness of the blank, the rod 64 will be almost in contact 10 with the lever 47.

Connected to the vertical member 60 by means of pivots 65 are a pair of levers 66 which in turn are pivoted through shaft 67 to a bell crank lever 68, itself supporting at 69 a control roll 70, and 15 being pivotally mounted on shaft 71 supported by control roll 72. A spring 73 normally urges the bell crank lever 68 in a counter-clockwise direction about its pivot 71 on the shaft of the control roll 72 and this movement is adapted to urge the 20 levers 66 into their position in Fig. 2 wherein the vertical member 60 will be positioned just under the horizontal arm 61 of the sleeve 62. The control roll 72 is itself adapted for rotation on the shaft 71, the roll and shaft being in turn rotatable with lever 73a about the stub shafts 74 carried by the side plates 10. The control roll 70 rotates, of course, on the shaft 69 as will be readily apparent.

Returning once again to lever member 57, I 30 prefer to have this lever spring pressed in a downward direction by the spring 75 maintaining the lever in its position of Fig. 2. Adjacent to the point where the lever 57 begins to extend upward, I mount a shaft 76 on which rotates the control roll 77, this roll being cut away at its center for the mounting of a further control member on the shaft, which will be described presently. The operation of the various parts just described is as follows.

40 As a sole or other moving blank 55 passes through the machine, it must enter under the control roll 77 and over the feed roll 19. Naturally, since the feed roll 19 is fixed, the sole 55 will force the control roll 77 in an upward direction, this upward movement being adapted to lift shaft 76 to force the lever member 57 vertically against the pressure of spring 75. This movement is well illustrated in Fig. 6 in which a blank 55 is shown as directly under the control roll 77, 45 and with the control roll lifted. This naturally functions through pivot shaft 59 to move the member 60 upward vertically, thus rotating the sleeve member 62 about the shaft 63 and causing the horizontal pin member 64 to move the 50 measuring levers 47 in a clockwise direction about their pivots 48. This causes the upward vertical movement of the measuring rolls 39 as will be readily understood. This position of the measuring rolls is maintained until the sole 55 reaches 55 a position directly under the control roll 70. It will be quite obvious that when it reaches the control roll 70, it will tend to move that roll upwardly against the pressure of the spring 73 exerted on the bell crank lever 68 on which the roll 60 is supported by pivot shaft 69. This will contribute a clockwise movement of the bell crank lever 68 about its pivot shaft 71 tending to move the horizontal levers 66 to the right from the position shown in Fig. 2 and to withdraw the member 60 from under the horizontal arm 61 of the sleeve 62. This, if the parts are positioned as in Fig. 6, will immediately release the sleeve 62 so that it will permit the measuring levers 47 to move to their position of Fig. 2 thus dropping the 75

measuring rolls onto the sole or blank for free measuring movement thereafter.

It will be readily understood that by this simple means, operated by the sole itself, I elevate the measuring rolls to a predetermined position, and when the sole has moved sufficiently under the measuring rolls as required by the particular arrangement of the machine, the sole itself acts to release the rolls for movement downward into proper position.

10 As was previously indicated, my invention is concerned also with the provision of means to control the initial actuation of the caster measuring wheels. It will be readily appreciated that as a sole or other blank enters the machine, and contacts the caster rolls, it will normally tend to strike those rolls so as to swing them to one side in a rather abrupt manner, the sole being moved at a fairly rapid speed. Also, since the sole may be slightly bent on one of its edges, it may on 15 many occasions contact the side of the caster rolls rather than their bottom surfaces, and throw the rolls aside, thus rendering them inoperative as measuring instruments, while at the same time, using the rolls as guides with which to sweep 20 aside the measuring arms 22. It is therefore necessary to provide means whereby the rolls will be locked in some particular position relatively to the arms 22 so that they cannot be swept to one side by the soles, while at the same time allowing the measuring arms to move freely as determined by the guide foot flanges 30.

25 I have provided caster roll controlling means whereby the rolls may be locked momentarily against substantial rotation relatively to arms 35 22, these means being operated directly with the means for controlling the lifting of the measuring rolls and their releasing movement downward into free measuring position. I secure to the sleeve member 62 a horizontal arm 79 to which is secured in turn a vertical member 80 which in turn is secured at 81 to an arm 82 pivoted to the shaft 67 which it will be recalled is carried by the bell crank member 68. The lever 82 has a horizontally extending member 83 which, when the sleeve 62 rotates in a counter-clockwise direction into the position of Fig. 6, is adapted to be actuated by the horizontal member 79 in a downward direction so as to cooperate with a detent 84 carried by each of the caster bearing 40 members 38.

45 Naturally, this will lock the casters 38 against movement relatively to the arms 22 until the sole travels into a position to operate the control roll 70 for releasing the measuring rolls 39 for 50 measuring movement, and also for swiveling movement by the release of the detent members 84 by the lever 82. In this way, I control both the locking of the caster rolls and their lifting and their releasing and lowering, by the same 55 means.

55 In Fig. 23 I illustrate a construction used with square end soles. I mount a cam 82a on the member 80, and place cams 31a on the arms 31. As the member 80 moves downward to lock the 60 rolls, it also spreads the two arms 22 by cooperation of the cam 82a with cams 31a. This allows a square end sole, such as shown in Fig. 22, to enter the machine. While other methods of spreading the arms 22 may be readily devised, 65 I find the particular construction quite effective.

70 The indicating mechanism of my machine is of the generally well known type wherein an indicator is allowed to move in a thinness indicating direction as induced by the measuring 75

rolls, under the control of pawl and ratchet mechanism. Just before the sole leaves the measuring rolls, a further pawl and ratchet mechanism is actuated for locking the indicator in a final position against movement into a zero thickness indicating position. There are, however, certain novel features in the control of my indicating mechanism and in its arrangement, which I believe are exceedingly novel and desirable in the art.

As previously, I shall describe the control over the indicator by one of the measuring levers 47 although as will be readily appreciated, it is the lever 47 which attains the greatest movement in a thinness indicating direction which controls the positioning of the indicator itself. The measuring lever 47, as shown in Fig. 2, carries an upstanding cup 85 adapted to house a lever and ball member 39 extending downwardly from the shaft 90 of an actuating member pivoted at 91 to a block member 92, which in turn is fastened in fixed relation to the indicating shaft 93. Through this arrangement, it is quite obvious that movement of the lever 47 in the direction of arrow 94 shown in Fig. 2, will urge the shaft 93 in a clockwise direction indicating increasing thinness of the moving blank in contact with the roll 39.

Also, it is apparent that whichever arm 47 moves upward further in the direction of arrow 94 will control the rotation of the shaft 93. Carried on the shaft 93 are a pair of ratchet members 95 and 96 and an indicator 97 (Figs. 7, 17, 18, 19). Ratchet 95 is the thinness indicating ratchet which is adapted to control the indicator 97 against movement in a direction indicating increasing thickness, once a particular indication of thickness has been obtained. The other ratchet member 96 is adapted to lock the indicator in a final position to prevent its movement into zero thickness indicating position. While the ratchets 95 and 96 may be fixed to shaft 93, I prefer that only one of the ratchets, 96, be secured to the shaft 93 while the other, 95, be loosely mounted on the shaft and held firmly against the ratchet 96 for integral movement therewith, by means of a rather strong spring 98 (Fig. 17), there being provided a screw stud 99a (Fig. 2) adapted to adjust the relationship of the two ratchets to compensate for any errors, as may be necessary. For the purpose of understanding the operation of the invention it may be considered, however, that the two ratchets are fixed to the shaft 93 for integral movement therewith, and so as to be operated together by movement of the measuring arms 47, which movement is adapted to rotate the shaft 93 through the intermediary of the crank block members 92.

60 A spring 99 is secured at one end to a member 100 and at 101 to a lever member 102 which in turn is pivoted on shaft 103a supported by the side members 10. The spring 99 thus tends to rotate the shaft 93 in a counter clockwise or thickness indicating direction whenever it is under tension. The lever member 102 is generally maintained in its position of Fig. 2 exerting tension on spring 99, so that the spring normally tends to rotate the indicator shaft 93 in a counter clockwise direction urging it into a thickness indicating direction and so that it may follow the movement of the measuring levers 47 in a direction opposite the arrow 94.

For controlling the ratchet member 95 I utilize a pawl member 103 which is also mounted

on the lever member 102 as at point 104 and is urged by a spring 105 in a counter clockwise direction into contact with the teeth 106 of the ratchet 95. A pin 107 carried by the lever 102 prevents the movement of the pawl into ratchet locking position when the parts are in the position of Fig. 2.

It is desirable, once the measuring rolls 39 have contacted with that portion of the sole to be measured, which in Fig. 13 is represented by 10 the line 108, that the ratchet 95 be locked against movement in a thickness indicating direction, that is, a direction counter-clockwise as shown in Fig. 2. For this purpose, I utilize the control roll 72 as is best illustrated in Fig. 7. This control roll 72 carries on its pivot shaft 74, as has already been indicated, the bell crank lever 68 which in turn supports the pivot shaft 67 which in turn carries the upwardly extending member 108. This member, is in turn connected through 15 a spring 109 with the lever member 102 and is adapted resiliently to control the movement of the lever member 102 through the spring 109 in both a counter clockwise and a clockwise direction, the counter-clockwise movement being 20 limited by a stop 102a carried by member 101a secured to shaft 103a. Thus, as a sole or other blank 55 enters under the roll 72, that roll will be rotated with its lever 73a about shaft 74, and will 25 act through member 108 to rotate the lever member 102 in a counter-clockwise direction about its shaft 103a so as to allow the pawl 103 to enter the ratchet teeth 106. Thereafter, it will be impossible for the ratchet lever 95 to move in a thickness indicating direction, the ratchet being 30 held against this movement by the pawl 103, although it will be free to move clockwise and in a thinness indicating direction as it may be positively urged by the measuring lever 47 through the vertical shaft 90. As soon as the 35 blank 55 passes from under the control roll 72 it will be obvious that the control roll 72 will drop downwardly and will rotate the lever member 102 in a clockwise direction and will act through stud 107 to throw the pawl 103 back 40 into its position of Fig. 2, thus releasing the 45 ratchet shaft 95.

It will, of course, be necessary at this point to have locked the shaft 93 to which the ratchet member 95 is secured, otherwise, the shaft 93 50 will rotate as urged by the spring 99 into a position indicating no thickness at all, since at this point, the blank 55 must naturally have passed from under the measuring rolls 39 which will then be in their zero thickness position of Fig. 2. 55 Therefore, there is required a further pawl controlling mechanism for controlling the ratchet 96 which is the final locking ratchet and which is locked in a final position just before a sole leaves the measuring rolls so as to prevent the 60 shaft 93 and the indicator 97 from moving into a zero thickness indicating position.

Before describing the operation of the final locking pawl and ratchet I shall indicate the operation of the admission gate, and the means 65 for controlling the tensioning of the spring 99. As is quite apparent from Fig. 2, the lever 102 has secured at its left end a vertical rod 110 which is connected at its lower point 111 to a gate member 112 pivoted at 113 to the lever members 70 71. When the pawl 103 is out of ratchet locking position as in Fig. 2, which position it occupies only after the sole has been completely measured, then the gate is in its upward position allowing a sole to enter the machine and between 75

the feed roll 19 and the control roll 77. However, when the machine is measuring a sole, that is when the pawl 103 is in contact with the ratchet teeth 106 as shown in Fig. 7, the gate 5 is naturally in a downward position and prevents the admission of a sole into the machine. In this way, I get a positive actuation of the gate in an in and out direction by the roll 72, which in turn is positively operated by the sole itself. 10 No timing is necessary for the gate, and its operation is positive in both directions.

There is a further means which is operated by the control roll 72 and the lever 102 in connection with the gate and the pawl 103, which is 15 of considerable importance in the operation of my invention and has already been emphasized. It will be understood that the spring 99 functions only to move the indicator 97 in a thickness indicating direction so as to follow the movement 20 of the arms 47 in a direction opposite the arrow 94 in Fig. 2. Now, once the pawl 103 moves into contact with the ratchet teeth 106, it is impossible for the ratchet bar 95 to move in a thickness indicating direction, and therefore, 25 the spring really ceases to function. However, when the member 96 is actuated positively by the measuring lever 47 in a thickness indicating direction, the spring pressure of the spring 99 must be overcome, and this creates considerable 30 inertia in the mechanism which in turn leads to inaccuracies in measuring. I, therefore, arrange the mechanism so that at the moment that lever 102 is rotated counter-clockwise the pawl 103 moves into contact with the ratchet teeth 106 to 35 lock the ratchet member 95 against movement in a direction indicating increasing thickness as urged by the spring 99, I at the same time relieve the tension on the spring 99 as is best illustrated in Fig. 7. Thereafter, the operation of the 40 ratchet member 95 will be entirely positive in a thickness indicating direction corresponding to a clockwise rotation of the shaft 93, and this movement will be free of any resistance by the spring 99 which will be maintained out of tension. It 45 is important to observe that this operation of the gate member 112, the spring tensioning and relieving means, and the locking pawl 103, is all arranged to be controlled by the one roll 72, the roll 72 being moved positively in its directional movements by the sole and the spring 73.

I shall now describe the operation of the final locking pawl in its cooperation with the ratchet 50 96 for locking the indicator in its final position just before the sole goes beyond the measuring 55 rolls 39 and into a position where the indicator 97 would normally register zero thickness. It is the function of the final locking pawl in its cooperation with the final locking ratchet to prevent such a zero indication. Just in advance of the 60 measuring roll, there is a depending foot 115 shown particularly in Figs. 20 and 21 and in Fig. 2, this foot being pivoted for movement about the pivot 116 on a block 117 secured to the shaft 76 on which is mounted the control roll 77.

Figs. 2 and 20 illustrate this foot in its fully 65 downward position, which position it occupies when a sole is not in contact therewith, the plate 52a being cut away to permit the foot to drop onto the plate 52d. In Fig. 21 the foot 115 70 is shown raised upward slightly as when contacted by a moving blank 55. The foot is so arranged as to move downwardly by gravity and to move upwardly when contacted by the sole. Connected to the foot 115 is a rod 118 which extends upwardly and is adapted to terminate in 75

a rod portion traversing an ear 119 of a block member 120 mounted on the shaft 103a (Figs. 2, 17-20). The rod has a shoulder 121 against which operates the spring 122 and it is through this spring that the rod 118 is adapted to rotate 5 the block 120 about the shaft 103a. A block member 123 pinned to the shaft 103a is adapted to limit the upper movement or the clockwise rotation of the member 120 about the shaft 103a as will appear quite clearly from a view of Fig. 17. 10

Mounted on the member 120 is the final locking pawl 124 which is constantly urged in a locking direction by a spring 125 and is controlled by the pin 126 carried by the member 120. It is quite obvious from Figs. 18 and 19 taken 15 together with Figs. 20 and 21, that when the foot member 115 is in its position of Fig. 20, the pawl 124 will be allowed to ride into the teeth 127 of the ratchet member 96 so as to lock the ratchet in final indicating position. On the other 20 hand, when a sole is under the foot 115, as shown in Fig. 21, the pawl 124 will be maintained out of contact with the ratchet teeth 127 so as to allow the indicator shaft 93 to have free movement in a thinness indicating direction. It will 25 be quite obvious that when the sole moves out from under the foot 115, which is just before the last portion of its edge is measured by the rolls 39, it will permit the foot 115 to drop and lock the indicator 97 in a final indicating position 30 through cooperation of the pawl 124 with ratchet teeth 127 as shown in Fig. 18. Thereafter, when the sole passes from under the rolls 39, the indicator will remain in a locked position.

It is interesting to note that because each pawl 35 is separately operated by a sole contacting member, it is inherent in the particular construction that the indicator remain in locked position until a further sole is fed into the machine, whereupon the indicator is released for free movement. 40 Thus, should there be some error in measuring the sole, the operator will not destroy the reading until he has sent a subsequent blank into the machine. Up until that point, however, the reading will be preserved for him. 45

In Figs. 14, 15 and 17, I have illustrated a modification of the final locking pawl whereby, when it moves into final locking position relatively to the ratchet teeth 127, it is adapted to close an electrical circuit through any one of a 50 series of lights 133 located at a bin 135, each light being indicative of a particular measuring unit. As is shown in Figs. 14 and 15 the pawl 124 carries a flexible contact 130 which is adapted to contact with one of a series of contacts 131 55 mounted opposite the teeth 127 in the ratchet member 96. The circuit is from a source of supply as 132 through the flexible contact member 130, any one of the contact members 131, and then through a filament bulb indicator 133 which 60 is in parallel with the condenser 134. The purpose of the condenser is such that should the machine be operated quite quickly, it will serve to maintain the current through the indicator bulb 133 for more than just a mere moment. 65

Also, it may be desirable in a modification of the invention, to connect the thinness measuring pawl and the final locking pawl so that the releasing of the thinness measuring pawl by the 70 passing of a sole from under the control roll 72, will be effective to release both pawls from holding position. In this type of construction the condenser 134 will be especially useful. Where, however, the two pawls are separately controlled, 75

it may not be necessary generally to use the condenser 134.

In Fig. 16 I show a bin 135 having a series of compartments 136, there being an indicator 133 for each of the compartments. With an apparatus of this type, it is only necessary for the operator to feed the blank into the machine, and then glance at the bin. As soon as the final locking pawl moves into locking position there will be rendered incandescent one of the signal lamps 133, and the operator has merely to take the particular sole just issued from the machine and throw it into the particular compartment indicated by the signal.

I employ also a very novel reversible apparatus for guiding a moving blank into the machine. This apparatus is especially shown in Figs. 2, 4 and 5. Reference numeral 138 represents a relatively fixed guide member which is spring pressed by a spring 139 as is shown in Fig. 4, its movement as urged by spring 139 being limited by a stop 140. It is against this member 138 that a moving blank 55, such as shown in Fig. 5, is adapted to be positioned. The blank is spring urged against the member 138 by a pair of members 141 and 142, each of these latter members being pivoted about the shaft 143.

The member 141 is spring urged by the spring 144 as is best illustrated in Fig. 4. The member 30 142 is spring urged in an exactly opposite rotational direction by a spring 145 as is best shown in Fig. 5. Its movement is limited by a pin 146 and it has an upstanding portion 147 operable in a slot 148. The member 141 has a downward 35 descending portion 149 and is limited in its movement by a pin 150. These two members 141 and 142 cooperate with the sole as best shown in Fig. 5, and urge it against the member 138. The springs 145 and 144 are relatively weak as compared to spring 139, so that the sole is maintained in fixed relation to the guide until it contacts the feed roll 19 and the control roll 77. Once it is grabbed by these rolls its guide members cease to be of effect, and both the guide 138 and the 40 guides 141 and 142 will be swept aside when the wide end 55a of the sole 55 goes past them. By this arrangement, it is quite easily seen that I have a relatively fixed guide member which functions as such until the sole is properly positioned 45 relatively to the machine, after which it may be swept aside to permit free admission of the sole into the machine. Also, because of the particular arrangement of the members 141 and 142, it is readily seen that they may be readily reversed for 50 left and right hand soles by merely releasing manual members 151 and 152, and turning over the entire assembly shown in Figs 2 and 5.

While I have thus described a particular modification of my machine, as I have already indicated previously, I consider this invention to be of broad scope, and I do not desire to be limited in the scope of my claims except as may be required by the state of the art.

I now claim:

1. In a machine of the class described, measuring rolls adapted to contact a blank to be gauged, means supporting said rolls for measuring movement perpendicularly to the plane of the blank, measuring or indicating means actuated by said 5 rolls in said movement, and means mounting said rolls on said supporting means for swivelling on an axis parallel to said measuring movement and offset in the manner of casters whereby they may be swivelled by directional variations relatively to a relatively moving blank they may be measuring.

2. In a machine of the class described, measuring rolls adapted to contact a blank to be gauged, means supporting said rolls for vertical measuring movement as the thickness of the blank varies, and means mounting said rolls on said supporting means in the manner of casters for swivelling on a vertical axis offset relatively to the point of contact of said rolls with said blank, whereby said rolls may swivel and assume various directional positions as the directional movement of said blank relatively to said rolls is varied. 5

3. In a machine of the class described, measuring rolls adapted to contact a blank to be gauged, means supporting said rolls for vertical measuring movement as the thickness of the blank varies, means mounting said rolls on said supporting means for swivelling in the manner of casters on a vertical axis offset relatively to the point of contact of said rolls with said blank, whereby said rolls may swivel and assume various directional positions as the directional movement of said blank relatively to said rolls is varied, and means for varying the directional movement of said blank relatively to said rolls as the contour of the blank changes. 20

4. In a machine of the class described, measuring rolls adapted to contact a blank to be gauged, means supporting said rolls for vertical measuring movement as the thickness of the blank varies, means mounting said rolls on said supporting means in the manner of casters on a vertical axis offset relatively to the point of contact of said rolls with said blank, whereby said rolls may swivel and assume different directional positions relatively to their 30 supporting means as the directional relation of the movement of said blank relatively to said rolls is varied, and means whereby said roll supporting means are moved in accordance with the changing contour of the measured blank to vary 35 the directional relation of said rolls and said blank. 40

5. In a machine of the class described, measuring rolls adapted to contact a blank to be gauged, mounting means mounting said rolls for vertical movement relative to said blank as the thickness of said blank varies, means supporting said rolls for swivelling relatively to said mounting means in the manner of casters and on an axis vertical relatively to said blank, means on an axis vertical relatively to said blank for moving said roll mounting means laterally relatively to said blank as the contour of the blank periphery changes, said lateral movement of the roll mounting means being effective to cause automatic 55 swivelling of the rolls in the manner of casters relatively to said supporting means when said rolls are in contact with the blank, so as to change the directional positions of said rolls to conform to the particular contour then effecting the movement of said mounting means. 60

6. In a machine of the class described, measuring rolls adapted to contact a blank to be gauged, means supporting said rolls for vertical measuring movement as the thickness of the blank varies, means mounting said rolls on said supporting means in the manner of casters on a vertical axis offset relatively to the point of contact of said rolls with said blank whereby said rolls will assume automatically a fixed directional position relatively to the supporting means as a blank is moved linearly relatively to said rolls, means responsive to the contour of the edge periphery of the blank for moving said supporting means laterally relatively to said 70 75

blank as the blank contour varies, said rolls being rotatable as casters relatively to the supporting means by the combination of their linear and lateral movement relatively to the blank whereby to position said rolls in directional alignment with the blank contour.

7. In a machine of the class described, a pair of swinging arms, measuring rolls mounted for vertical measuring movement relatively to said arms and adapted to receive measuring movement when contacted by a moving blank, means contacting the periphery of the blank for swinging the arms in conformance to the contour of said blank, said rolls being mounted for swiveling movement relatively to said arms, the pivots for said swivels being offset relatively to the contact point of said rolls on the blank, whereby said rolls will have a caster movement so as to follow more accurately the edge contour of said blank.

8. In a machine of the class described, a measuring roll adapted to contact a blank to be measured, a member on which said roll is supported, means whereby said roll is pivoted to said member on an offset vertical axis so that it may swivel relatively to said member in the manner of a caster, said roll being secured for integral movement with said member in a vertical direction as the thickness of the blank varies, a pivoted measuring lever connected to said member for pivotal measuring movement as said member and its roll move vertically, and means for guiding said member in a path to maintain the swivel axis perpendicular to the plane of the blank whereby to give the true measurement of said blank regardless of the angular position assumed by said offset roll relatively to said member.

9. In a machine of the class described, a measuring roll adapted to contact a blank to be measured, a member on which said roll is supported, means whereby said roll is pivoted to said member on a vertical axis offset relatively to the point of contact of said roll with said blank so that it may swivel relatively to said member in the manner of a caster, said roll being secured for movement with said member in a vertical direction as the thickness of the blank varies, and means for guiding said member in a path to maintain the swivel axis perpendicular to the plane of the blank whereby to give the true measurement of said blank regardless of the angular position assumed by said offset roll relatively to said member.

10. In a machine of the class described in which a blank is movable therethrough in a horizontal plane, a measuring arm, a measuring lever pivoted to said arm for movement in a vertical plane, a guide lever also pivoted to said arm for movement in a vertical plane, a member pivoted to said guide lever and to said measuring lever and in such relation that it is always maintained in fixed angular relation to the blank by said levers, a measuring roll adapted to contact a blank to be measured, means mounting said measuring roll for pivotal movement on said member on an axis maintained through said levers perpendicular to the plane of the moving blank, said axis being offset relatively to the point of contact of the roll relatively to the blank, and means whereby said roll and members are movable together upon variation of the thickness of said blank to operate said measuring lever.

11. In a machine of the class described in which a blank is movable therethrough in a horizontal plane, a measuring arm, a measuring le-

ver pivoted to said arm for movement in a vertical plane, a guide lever also pivoted to said arm for movement in a vertical plane, a member pivoted to said guide lever and to said measuring lever and in such relation that it is always maintained in fixed angular relation to the blank by said levers, a measuring roll adapted to contact a blank to be measured, means mounting said measuring roll for pivotal movement on said member on an axis maintained through said levers perpendicular to the plane of the moving blank, said axis being offset relatively to the point of contact of the roll relatively to the blank, means whereby said roll and member are movable together upon variation of the thickness of said blank to operate said measuring lever, and a spring for maintaining said roll and member against the blank.

12. In a machine of the class described in which a blank is movable therethrough in a horizontal plane, a measuring arm, a measuring lever pivoted to said arm for movement in a vertical plane, a guide lever also pivoted to said arm for movement in a vertical plane, a member pivoted to said guide lever and to said measuring lever and in such relation that it is always maintained in fixed angular relation to the blank by said levers, a measuring roll adapted to contact a blank to be measured, means mounting said measuring roll for pivotal movement on said member on an axis maintained through said levers perpendicular to the plane of the moving blank, said axis being offset relatively to the point of contact of the roll relatively to the blank, said roll and member being movable together upon variation of the thickness of said blank to operate said measuring lever, and means for swinging said arm in response to the contour of the blank whereby to swivel said roll in the manner of a caster to follow the edge contour of the blank.

13. In a machine of the class described, measuring arms, measuring rolls mounted for vertical measuring movement relatively to said arms and adapted to receive measuring movement when contacted by a moving blank, means mounting said rolls whereby they may follow the edge contour of the moving blank with substantially the same predetermined portions of the rolls contacting the edge of the blank, and means mounting said rolls so that they may tilt on an axis transverse to their axis of rotation and with the vertical orientation of said predetermined portions remaining unchanged regardless of tilting, whereby to follow any surface irregularities of the blank edge.

14. In the combination of claim 7, means mounting said rolls for tilting movement on an axis transverse to their axis of rotation so that they may take inclined positions conforming to irregularities in the blank edges.

15. In the combination of claim 7, means positioning said rolls so that their exact center coincides with the edge of the moving blank, and means for mounting said rolls for tilting movement on an axis transverse to their axis of rotation so that they may take inclined positions conforming to irregularities in the blank edges.

16. In a machine of the class described, measuring rolls mounted for vertical movement and adapted to have measuring movement transmitted to them by a moving blank, control means positioned in advance of said rolls and adapted to be operated by said moving blank, and means operated by said control means to elevate said rolls to permit the blank to enter under them.

17. In a machine of the class described, measuring rolls mounted for measuring movement and adapted to have measuring movement transmitted to them when contacting a relatively moving blank of varying thickness, and means in advance of said rolls actuated by contact with the relatively moving blank for elevating the rolls to permit the blank to enter under the elevated rolls for measurement by said rolls.
18. In a machine of the class described, measuring rolls mounted for measuring movement and adapted to have measuring movement transmitted to them when contacting a relatively moving blank of varying thickness, measuring means operated by said rolls, blank contacting means positioned in advance of said measuring rolls, said contacting means being movable by said blank, and means operable by said contact means for moving said measuring means and for lifting the measuring rolls through said measuring means to permit entry of the blank under said rolls.
19. In a machine of the class described, measuring rolls mounted for measuring movement and adapted to have measuring movement transmitted to them when contacting a relatively moving blank of varying thickness, a blank contacting roll positioned in advance of said measuring roll and adapted to be lifted by the blank, a lever member and a supporting means for said roll secured to said lever for lifting the same, and means operable by said lever for lifting said measuring rolls a distance proportional to the lifting of said contacting rolls whereby to facilitate entry of the blank under the rolls.
20. In a machine of the class described, measuring rolls mounted for measuring movement and adapted to have measuring movement transmitted to them when contacting a relatively moving blank of varying thickness, and means in advance of said rolls actuated by contact with the relatively moving blank for elevating the rolls to permit the blank to enter under the elevated rolls for measurement by said rolls, and means stationed beyond said measuring rolls actuated by said blank to permit the rolls to drop onto the moving blank.
21. In a machine of the class described, measuring rolls mounted for measuring movement and adapted to have measuring movement transmitted to them when contacting a relatively moving blank of varying thickness, measuring means operated by said rolls, blank contacting means positioned in advance of said measuring rolls, said contacting means being movable by said blank, and means operable by said contact means for moving said measuring means and for lifting the measuring rolls through said measuring means to permit entry of the blank under said rolls, and a blank contacting means stationed just beyond the measuring rolls for releasing the measuring rolls whereby they may drop on the moving blank.
22. In a machine of the class described, measuring rolls mounted for measuring movement and adapted to have measuring movement transmitted to them by a moving blank, control means stationed in advance of said rolls and control means stationed just beyond said rolls and adapted to be operated by the moving blank, means operated by said advance control means to elevate said rolls to permit the blank to enter under the rolls, and means operated by the second control means for dropping said rolls on to the blank.
23. In the combination of claim 1, means for locking said measuring rolls against substantial swivelling movement until after they have contacted the moving blank.
24. In a machine of the class described, measuring rolls adapted to contact a blank to be gauged, means mounting said rolls so that they may move vertically as the thickness of the blank varies, measuring or indicating mechanism operated by said vertical movement, means mounting said rolls for free swivelling movement while moving vertically whereby they may be guided relatively to the edge contour of the blank, and means operable by a relatively moving blank for locking the measuring rolls against swivelling movement until after they are positioned over the said moving blank.
25. In a machine of the class described, measuring rolls adapted to contact a blank to be gauged, means mounting said rolls so that they may move vertically as the thickness of the blank varies, measuring or indicating mechanism operated by said vertical movement, means mounting said rolls for free swivelling movement while moving vertically whereby they may be guided relatively to the edge contour of the blank, blank contacting means positioned in advance of said measuring rolls, said contacting means being operable by a moving blank for effecting the locking of said measuring rolls against substantial swivelling movement until after the blank is positioned under the rolls.
26. In a machine of the class described, measuring rolls adapted to contact a blank to be gauged, means mounting said rolls so that they may move vertically as the thickness of the blank varies, measuring or indicating mechanism operated by said vertical movement, means mounting said rolls for free swivelling movement while moving vertically whereby they may be guided relatively to the edge contour of the blank, blank contacting means positioned in advance of said measuring rolls, said contacting means being operable by a moving blank for effecting the locking of said measuring rolls against substantial swivelling movement until after the blank is positioned under the rolls, and a blank contacting means positioned beyond the rolls and operable to release the rolls when contacted by the blank.
27. In the combination of claim 7, means for locking said measuring rolls against substantial swivelling movement until after they have contacted the moving blank, control means positioned in advance of said measuring rolls and control means positioned just beyond said measuring rolls and adapted to be operated by the moving blank, means operated by said advance control means to operate said roll locking means and to elevate said rolls to permit the blank to enter under the rolls, and means operated by the second control means to release said rolls for swivelling and to drop them on to the blank.
28. In a machine of the class described, measuring rolls adapted to contact a blank to be gauged, means mounting said rolls so that they may move vertically as the thickness of the blank varies, measuring or indicating mechanism operated by said vertical movement, means mounting said rolls for free swivelling movement while moving vertically whereby they may be guided relatively to the edge contour of the blank, control means positioned just in advance of said measuring rolls, control means positioned just beyond said measuring rolls, said control means being operable by a moving blank, means oper-

- able by said advance control means when contacted for locking said rolls against swivelling and elevating said measuring rolls so as to permit the blank to enter under the rolls, and means 5 operable by said second control means for releasing the rolls for swivelling and for dropping them onto the blank.
29. In a machine of the class described, thickness measuring rolls, an indicator operable by 10 said measuring rolls as said rolls contact a moving blank, pawl and ratchet mechanism for preventing movement of said indicator in a direction indicating greater thickness once a particular indication has been transmitted to said indicator, 15 and control means physically contacted by said blank in its movement through the machine for moving said pawl and ratchet into cooperative engagement and adapted to move said pawl and ratchet out of engagement as said blank passes 20 out of physical contact with said control means.
30. In a machine of the class described, a measuring roll, an indicator movable by said roll as said roll contacts a relatively movable blank, pawl and ratchet mechanism for preventing movement 25 of said indicator in a direction indicating greater thickness, a gate positioned just in advance of said measuring roll, a blank contacting device positioned just beyond the measuring roll, a lever carrying the pawl of said pawl and ratchet 30 mechanism and connected with said gate, and means for moving said lever into pawl and ratchet engaging position and gate lowering position upon operation of said blank contacting device by a blank, and for releasing the pawl and ratchet 35 and raising the gate upon movement of the blank beyond said device.
31. In a machine of the class described, thickness measuring rolls, an indicator operable by 40 said measuring rolls as said rolls contact a moving blank, pawl and ratchet mechanism for preventing movement of said indicator in a direction indicating greater thickness once a particular indication has been transmitted to said indicator, a gate adapted to prevent entrance of a 45 blank into the machine, and control means physically contacted by said blank in its movement through the machine for simultaneously moving said pawl and ratchet into cooperative engagement, and said gate into entrance blocking 50 position, and adapted to move said pawl and ratchet out of engagement and said gate out of blocking position as said blank passes out of physical contact with said control means.
32. In a machine of the class described, thickness 55 measuring rolls, an indicator, means whereby said indicator is movable positively by movement of said rolls in a thinness indicating direction, a spring adapted to press said indicator in a thickness indicating direction so as to follow 60 the movement of said rolls in a thickness indicating direction, pawl and ratchet mechanism for preventing movement of said indicator in a direction indicating greater thickness once a particular indication has been transmitted to said 65 indicator while permitting movement of said indicator in a thinness indicating direction, and means for relieving the tension of said spring operable at a predetermined point in the operation of the machine whereby to relieve the 70 inertia of said indicator against movement in a thinness indicating direction.
33. In a machine of the class described, thickness 75 measuring rolls, an indicator operable by said rolls, means for locking said indicator in a final indicating position, control means for said locking means operable by a moving blank, said control means being operable into indicator locking position when left behind by a moving blank, said means being operable into indicator releasing position when contacted by a moving blank and adapted to remain in releasing position while in said blank contacting position.
34. In a machine of the class described, a gate for controlling the admission of a moving blank, 10 scale measuring rolls positioned beyond said gate, an indicator operated by said measuring rolls, 15 detent means for locking said indicator against movement in a thickness measuring direction, a final locking detent means for locking said indicator against movement in a thinness measuring direction, a series of moving blank operated control devices operated by a blank moving through said machine, one of said devices being adapted to move the gate and thickness locking detent in and out of blocking and locking position respectively, and a second one of said devices being operable to move the final locking detent in and out of locking position.
35. In a machine of the class described, a moving blank centering assembly comprising a guiding member, a spring pressed member adapted to press the moving blank against said guiding member so as to guide the blank into the machine, a pair of feed rolls into which the blank is fed as determined by said guiding member, and 20 means whereby said guiding member may be moved to one side once said blank is grasped and fed by said feed rolls.
36. In a machine of the class described, a moving blank centering assembly comprising a guide 25 member spring pressed by a relatively heavy spring into a predetermined position, a spring pressed member adapted to press the moving blank against said guide, a pair of feed rolls into which the blank is fed and adapted to permit 30 of no side movement of the blank after grasping the same, said guide member and said spring pressed member being movable to one side as required by the blank once it is securely positioned in said feed rolls, said assembly being 35 readily reversible as a unit for use with right and left foot soles.
37. In a machine of the class described, a pair 40 of swinging measuring arms, measuring rolls carried by said arms, means secured to said arms for swinging them so as to follow the periphery of a moving blank to be measured, a control device positioned just ahead of said arms and adapted to be first contacted by said moving blank, and means actuated by said device when 45 contacted by the blank for swinging said arms apart to permit the movement therebetween of a square end blank itself ineffective to cam the arms apart.
38. In a machine of the class described, a measuring arm mounted for swinging movement to follow the edge contour of a blank to be measured, means in contact with the edge of the blank whereby said arm is actuated to follow the edge 50 contour of the blank to be measured, means urging said arm to a predetermined position, and means in the machine operable at a predetermined time in the cycle of the machine for swinging said arm to one side from said position, to permit a blank to enter into contact relation 55 therewith.
39. In a machine of the class described, a pair 60 of measuring arms mounted for swinging movement to follow the contour of a blank and normally maintained in a central position, and 65

means in the machine operated by contact with the blank at a predetermined time in the cycle of the machine for swinging said arms apart from said central position to permit the entry of the blank between the arms.

40. In a machine of the class described, a pair of measuring arms pressed into a neutral position and adapted to press against the edges of a blank entered between the arms so as to follow the blank contour, blank contacting means positioned in advance of said arms, said contacting means being operable by a moving blank for swinging said arms aside to permit the entry of the blank between them.

41. In a machine of the class described, a pair of measuring arms pressed into a neutral position and adapted to press against the edges of a blank entered between them so as to follow the blank contour, blank contacting means positioned in advance of said arms, means operable by said blank contacting means when contacted by the blank for swinging said arms aside to permit entry of the blank between the arms, and a blank contacting means positioned beyond the arms and operable when contacted by the blank to effect swinging of the arms into contact with the blank.

42. In a machine of the class described, a feed plate, a guide member, a spring adapted to maintain said guide member in a predetermined position, a second guide member, a spring of considerably less power than said first spring pressing said second guide member in a manner urging a blank against said first guide member whereby to position said blank for feeding into the machine, said plate being reversible to adapt itself to right and left foot soles.

43. In a machine of the class described, a feed plate, a guide member, a spring adapted to maintain said guide member in a predetermined position, a spring pressed member for urging a blank against said guide member to position said blank for feeding into the machine, the spring pressing said member being of substantially less strength than said first spring, said guide member and said spring pressed member being both arranged for swinging to one side as the sole is gripped and fed into the machine.

44. In a machine of the class described, a pair of measuring levers, means mounting said levers for vertical measuring movement and for horizontal swinging movement, measuring rolls adapted to contact a moving blank to be measured and connected to said levers for moving the same, means whereby each of said rolls may swivel on a vertical axis relatively to said levers with said axis offset relatively to the point of contact of said rolls with said blank, means for swinging said levers as the contour of the blank changes, said horizontal swinging movement being effective to cause swivelling of the measuring rolls on their axes so that said rolls may follow the contour of the blank.

45. In a machine of the class described, a measuring roll adapted to contact a blank to be measured, a supporting member on which said roll is pivoted for swivelling movement in response to the blank contour on an axis offset from the point of contact of the roll relatively to the blank, a spring urging said roll into a particular rotated position relatively to its supporting means, and against the pressure of which it is adapted to swivel in response to the blank contour.

46. In a machine of the class described, a

measuring roll adapted to contact a blank to be measured, a supporting member on which said roll is pivoted for swivelling movement on an axis offset from the point of contact of the roll relatively to the blank, a spring urging said roll into a particular rotated position relatively to its supporting means, and against the pressure of which it swivels, a further spring urging said supporting member against the blank being measured, and a guide foot on said supporting member adapted to impinge against the blank to guide said member.

47. In a machine of the class described, a measuring roll adapted to contact a blank to be measured, means mounting said roll for vertical measuring movement and for swivelling in a vertical axis whereby to adjust said roll for blank contour following movement, a stationary plate over which said blank passes, said plate being mounted so as to underly said roll in every position thereof while it is swivelling relatively to said plate.

48. In a machine of the class described, a horizontally swinging arm, a guide carried by said arm and adapted to engage a blank for swinging the arm as the contour of the blank changes, a measuring roll carried by said swinging arm and movable therewith, said roll and guide being so related that when the guide is in contact with the blank for guiding the arm, the measuring roll is positioned at the edge of the blank, means mounting said roll for bodily swivelling movement relatively to said arm in the manner of a caster on an axis offset relatively to the point of contact of said roll with said blank, whereby said roll is positioned continuously by its contact with the blank and the swinging of the arm, so as to ride along the edge of the blank regardless of the changes in contour of the blank.

49. In a machine of the class described, a horizontally swinging arm, a guide carried by said arm and adapted to engage a blank for swinging the arm as the contour of the blank changes, a measuring roll carried by said swinging arm and movable therewith, said roll and guide being so related that when the guide is in contact with the blank for guiding the arm, the measuring roll is positioned with its midpoint substantially on the edge of the blank, means mounting said roll for bodily swivelling movement relatively to said arm in the manner of a caster on an axis offset relatively to the point of contact of said roll with said blank, whereby said roll is positioned continuously by its contact with the blank and the swinging of the arm to ride along the edge of the blank regardless of the changes in the contour of the blank.

50. In a machine of the class described, a horizontally swinging arm, a guide carried by said arm and adapted to engage a blank for swinging the arm as the contour of the blank changes, a measuring roll carried by said swinging arm and movable therewith, said roll and guide being so related that when the guide is in contact with the blank for guiding the arm, the measuring roll is positioned with its midpoint substantially on the edge of the blank, means mounting said roll for bodily swivelling movement relatively to said arm in the manner of a caster on an axis offset relatively to the point of contact of said roll with said blank, whereby said roll is positioned continuously by its contact with the blank and the swinging of the arm to ride along the edge of the blank regardless of changes in contour.

of the blank, and means mounting said roll also for tilting movement whereby it may follow angular irregularities of the edge of the blank.

51. In a machine of the class described, a swinging arm, a thickness measuring roll carried by said swinging arm and adapted to contact a blank to be measured and to move in conformity with the thickness of the blank, means mounting said roll on said swinging arm in an offset axis 10 relatively to its point of contact with the blank and in the manner of a caster for bodily swivelling blank contour following movement, means whereby said arm swings in accordance with the changes in the contour of the blank to be measured and moves the measuring roll therewith, 15 a plate over which said blank passes, said plate being mounted so as to underlie said roll in every

position thereof while it is swivelling relatively to said plate, incidental to its actuation by a moving blank and the swinging movement of said arm.

52. In a machine of the class described, measuring rolls mounted for measuring movement and adapted to have measuring movement transmitted to them when contacting a relatively moving blank of varying thickness, said rolls lying normally in a minimum thickness position, means operated by the relatively moving blank 10 for elevating the rolls to permit the blank to enter freely under the rolls for measurement by said rolls, and means contacted by the said blank thereafter for releasing said rolls to drop on to said blank. 15
